[57] CLAIM

The ornamental design for a hot button keyboard, as shown and described.

DESCRIPTION

FIG. 1 is a front, right, and top perspective view of a hot button keyboard showing my new design;

FIG. 2 is a top plan view thereof;

FIG. 3 is a bottom plan view thereof;

FIG. 4 is a left-side elevational view thereof;

FIG. 5 is a right-side elevational view thereof;

FIG. 6 is a front elevational view thereof; and,

FIG. 7 is a rear elevational view thereof.

The keys are shown in broken lines in the figures for illustrative purposes only and form no part of the claimed design.
